CLAIM

The ornamental design for a display screen with a graphical user interface, as shown and described.

DESCRIPTION

3. Display screen with a graphical user interface
 The single FIGURE is a front view of a display screen with a graphical user interface.

The broken lines showing the display screen and portions of the graphical user interface form no part of the claimed design.

Design 3 relates to a graphical user interface showing a perspective view of a vehicle compartment including a dashboard and a tunnel as displayed on a screen; the broken lines are for the purpose of illustrating a generic background and form no part of the claimed design.
